TRIPLE MIRROR ILLUMINATED COMPACT

William Dawson, Toronto, Ontario, Canada

Application February 24, 1941, Serial No. 380,212
In Canada December 11, 1940

3 Claims. (Cl. 132—83)

My invention relates to certain new and useful improvements in compacts which are carried in a purse or handbag and contain cosmetic accoutrement.

An object of the invention is to produce a compact incorporating an electric light source by which it can be illuminated when extraneous light is insufficient or not available. More particularly the invention provides for the shedding of light upon the mirror with which the compact is equipped and also upon the face of the person using the same.

A further object is to construct a compact with a triple mirror constituting a lid that can be opened to a reclining position and the side pieces unfolded to a suitable angle as required in the application of the cosmetics, the light source being so disposed as to illuminate the reflective faces of the mirror.

A distinctive feature of construction resides in the arrangement of a reflector at the base of the lamp for the upward and outward emission of light, and another feature is contained in the novel structure of the battery compartment and switch.

The invention will be better understood by reference to the accompanying drawing, in which Figure 1 is a perspective view of the closed compact.

Figure 2 is a similar view showing the lid of the cosmetic compartment partly open and the lid of the battery compartment fully open.

Figure 3 illustrates the compact opened for use.

Figure 4 is a longitudinal section.

Figure 5 is a plan in section taken on line 5—5 of Figure 4.

Figure 6 is a cross section on line 6—6 of Figure 4.

Like numerals of reference designate similar parts in each view of the drawing.

In constructing my device, I provide a shallow rectangular case 1 of suitable proportions to supply an upper tray 2 and a lower battery compartment 3. The case is somewhat elongated as shown and the top, which is open to expose the tray, is normally closed by a lid 4. The body of the case is composed of rigid walls of suitable material such as metal, and the lid 4 extends longitudinally of the body for substantially its entire length and is hingedly connected at its rear end for swinging upwardly to a backwardly inclined position as depicted in Figure 3. A pull piece of approved form is supplied on the top of the lid, as at 5, by which it is operated.

The opening for said lid is formed in part by a narrow transverse wall 6 integral with the front wall 7 that extends to the bottom wall 2' of the tray 2, and below this front wall is an opening leading into the battery compartment 3 that is normally closed by a lid 8 hinged at 9 and equipped with a pull 10 in addition to a customary catch—not shown. Said opening for the lid 4 is also formed in part by a narrow transverse wall 11 integral with the rear wall 12 of the body and having a frontal edge that serves as an abutment shoulder for this lid in order to maintain it in an inclined position when open. This lid is hinged on a transverse pintle 13 secured to the sides of the body and the knuckle is carried by the angular flanges 13' to enable the lid to swing properly. The interior face of the lid is a mirror and the sides have inwardly projecting supports 14 that hingedly carry wing mirrors 15 that are unfolded to compose a triple mirror construction. The wing mirrors fold inwardly to lie parallel with the lid in closing the same.

The top of the tray is disposed below the top 25 of the body so as to provide clearance for the triple mirror, and hinged covers 16 are supplied for folding over and thus protecting the cosmetics within the tray, which is of a capacity to contain the usual preparations common to compacts. The tray is preferably rigidly mounted in the case-body and extends rearwardly but terminates short of the hinged part of lid 4 to provide a lamp well.

The lamp well accommodates an arcuate reflector 17 that is upturned and transversely secured at its ends to the side walls of the body. The reflector, which is a metal member, has a medial socket 18 in which is fitted a standard bulb 19, the base of which extends below the reflector and is of the single contact type.

An ordinary battery 19' is lodged in the compartment 3 below the tray with its terminal posts 20 and 20' projecting rearwardly below the lamp well. Terminal 20 is bent to engage the contact 45 at the bottom of the base of the bulb, and the other contact, 20', is angularly disposed whereby it may be engaged by an arm 21 of a switch slide 22 slidable endwise in a guideway of a side wall of the body. The slide is shifted by a button or the like 23.

It will be evident that the electric circuit between the battery and the bulb is established by closing the switch for the reason that the reflector and the casing body serve as a ground for the switch.

It will also be manifest that due to the disposition of the bulb and its reflector light rays will be emitted in the most desirable manner for effectively illuminating the compact in its use with its triple mirror construction.

I claim:

1. A compact of the class described comprising a case having a compartment accessible by an opening, a closure for said opening including an interior mirror that is swung to a backwardly inclined position in the opening of the closure, wing mirrors at the sides of said mirror, and supports mounting said wing mirrors on the closure so that they may unfold outwardly when the closure is opened, the structure being characterized in that the said supports project inwardly from the closure and are hinged to the wing mirrors which enable the wing mirrors to fold flat in co-planar relation so as to occupy a minimum of space when not in use.

2. A compact of the class described comprising a case having a compartment accessible by an opening in its top, a tray in said compartment for containing cosmetics, said tray being disposed below the top of the case, a lid for said opening hingedly mounted at the rear thereof and swingable upwardly to a sustained backwardly inclined position, the inner face of said lid being a mirror, wing mirrors at the sides of said mirror, and supports hingedly mounting said wing mirrors on the lid inwardly of said mirror so that the wing mirrors may be folded flat against the same to clear said tray when the lid is closed.

3. A compact comprising an elongated rectangular case-body of a shallow construction having a top opening extending the full length

of the body with the exception of narrow transverse top walls at the ends thereof respectively integral with front and rear end walls, a lid normally closing said opening and hinged at the rear thereof by a pintle transversely secured to the sides of the body such that the lid may swing upwardly to a rearwardly inclined position in which it abuts the rear transverse top wall of the body, the inner face of said lid being constructed as a mirror, supports extending inwardly of the sides of the lid, wing mirrors hingedly carried by said supports for unfolding to compose a triple mirror, a depressed tray within said body providing clearance for the wing mirrors when the lid is closed, said tray having hinged cover pieces and dividing the body into an upper compartment and a lower compartment, the tray extending rearwardly and terminating short of the hinge of the lid to define a lamp well, the lower compartment being accessible by an opening in the front of the body supplied with a closure, an arcuate reflector disposed in the lamp well with its ends secured at the sides of the body, said reflector being spaced from the bottom of the body and having an intermediate socket, an electric bulb in the socket with its base projecting below the reflector, a battery in the lower compartment aforesaid having a pair of terminal posts, one of which is bent to engage a contact of the bulb-base, a slide switch having an arm for contact with the other terminal post of the battery, and means forming a conductor between the bulb and the switch such as to complete the circuit when the switch is closed.

WILLIAM DAWSON.
